Primary Examiner—Martie Thompson*Attorney, Agent, or Firm*—Watts, Hoffmann, Fisher & Heine Co., L.P.A.[57] **CLAIM**

The ornamental design for a combined writing instrument and pocket holder therefor, as shown and described.

DESCRIPTION

FIG. 1 is a front perspective view of a combined writing instrument and pocket holder therefor showing my new design;

FIG. 2 is a front perspective view of a second embodiment of my design of FIG. 1;

FIG. 3 is a front perspective view of a third embodiment of my design of FIG. 1;

FIG. 4 is a front perspective view of a fourth embodiment of my design of FIG. 1;

FIG. 5 is a bottom view of any of the embodiments of FIG. 1-4;

FIG. 6 is a front elevational view of FIG. 1;

FIG. 7 is a side elevational view of FIG. 1, the opposite side being a mirror image thereof;

FIG. 8 is a rear elevational view of FIG. 1;

FIG. 9 is a top view of the pocket portion of FIG. 1, shown separately for ease of illustration;

FIG. 10 is a top view of the pocket portion of FIG. 2;

FIG. 11 is a top view of the pocket portion of FIG. 3;

FIG. 12 is a top view of the pocket portion of FIG. 4;

FIG. 13 is a perspective view of the writing instrument portion of FIGS. 1 and 3, shown separately for ease of illustration;

FIG. 14 is an elevational view of the writing instrument portion of FIG. 13 which is any of a front, back or either side elevational view;

FIG. 15 is a bottom view of the preferred writing instrument portion of FIGS. 13 and 14;

FIG. 16 is a top view of the writing instrument portion of FIGS. 13 and 14;

FIG. 17 is a perspective view of the writing instrument portion of FIGS. 2 and 4, shown separately for ease of illustration;

FIG. 18 is a bottom view of the writing instrument portion of FIG. 17;

FIG. 19 is an elevational view of the writing instrument portion of FIGS. 17 and 18 as seen from the plane indicated by the line 19—19 of FIG. 18;

FIG. 20 is an elevational view of the writing instrument portion of FIGS. 17-19 as seen from the plane indicated by the line 20—20 of FIG. 18;

FIG. 21 is a top view of the writing instrument portion of FIG. 17; and,

FIG. 22 is an elevational view of the writing instrument portion of FIG. 17 having a slightly modified lower end portion.
